UNITED STATES PATENT OFFICE

THOMAS E. MCNULTY, OF ALAMEDA, CALIFORNIA

GUIDE FOR VENETIAN BLINDS

Application filed February 16, 1929. Serial No. 340,519.

This invention relates particularly to a guiding apparatus for Venetian blinds.

An object of the invention is to provide a guideway on each of the opposite vertical sides of a window or door opening within which Venetian blinds may be mounted, to guide the opposite sides of the said blinds in the up and down travel thereof when being moved into the collapsed or extended positions.

A further object of the invention is to provide a guide for Venetian blinds consisting of a pair of wires separated a predetermined distance and adapted to receive therebetween

15 a slider mounted on the ends of each of the strips forming a Venetian blind, to maintain the entire blind in a predetermined position relative to the opening within which it is arranged and to also maintain each of the 20 strips comprising the blind, in a predetermined relation relative to each other.

A still further object of the invention is to provide a slide member to be attached to each of the strips comprising a Venetian blind 25 that consists of a base portion, a neck portion, and a head portion, the base portion being adapted to be suitably located on the strip of the blind to confine the neck portion between the wires of the guideway, 30 whereby the said slide is free to move vertically and to eliminate the possibility of either the slide or the strip from contacting with any part of the window or door opening within which the Venetian blind is 35 mounted to interfere with the free movement thereof.

Other objects of the invention are to provide a guiding apparatus for Venetian blinds that will be superior in point of simplicity, inexpensiveness of construction, 40 positiveness of operation, and facility and convenience in use and general efficiency.

In this specification and the annexed drawings, the invention is illustrated in the form 45 considered to be the best, but it is to be under-

stood that the invention is not limited to such form, because it may be embodied in other forms; and it is also to be understood that in and by the claims following the description, it is desired to cover the invention in whatsoever form it may be embodied.

In the accompanying one sheet of drawings:

Fig. 1 represents a vertical cross section, partly broken away, through the upper end 55 of a window or door opening having a Venetian blind therein, and a guiding apparatus therefor constructed in accordance with my invention.

Fig. 2 is a front elevation of a fragmentary portion of the Venetian blind guiding apparatus shown in Fig. 1.

Fig. 3 is a plan section taken through Fig. 1, on the line 3—3.

Fig. 4 is a fragmentary detail in perspective of one of the sliders for the strips of the Venetian blind confined between the vertical guides.

Fig. 5 is a perspective view of one of the bridges for holding the wire guides in spaced relation.

Fig. 6 is a side elevation of the lower part of a fragmentary portion of a window opening showing my apparatus for guiding the Venetian blind.

Fig. 7 is a modified form of the invention showing the guiding apparatus for the Venetian blind projected out from the face of the opening within which the said blind may be mounted.

Fig. 8 is a plan section taken through Fig. 7 on the line 8—8.

Fig. 9 is a section taken through Fig. 7 on the line 9—9.

Fig. 10 is a section taken through Fig. 9 on the line 10—10.

In detail the construction illustrated in the drawings comprises a jamb 1, of a window or door, or other analogous enclosure, within which a Venetian blind is mounted. It is to

be understood that only a detail of one side of a complete opening is shown, and the connections of the strips of the blind on one side only, to the guiding apparatus is indicated 5 inasmuch as the connection of the blind on the opposite side of the opening to the guiding apparatus is precisely the same.

This invention is designed primarily for Venetian blinds of a conventional type, which 10 usually consist of a series of flat strips joined together in such a manner that when arranged across the entire area of a window or door opening, the said strips may be adjusted into any desired angle to regulate the amount of 15 light that may pass through the opening, and also the said strips may be drawn together into a relatively tight and compact stack of strips.

In Figs. 1 and 6, the jamb 1 extends from 20 the head of the opening to the bottom thereof, and on the face of said jamb, adjacent the upper and lower ends thereof, I have mounted a bridge 2, such as shown in Fig. 5. Each of the bridges 2 are secured to the face 25 of the jamb 1, by a fastening screw 3, or other equivalent attaching medium. A wire 4 has one end thereof looped around the screw 3 and is twisted upon itself between the head of the screw and the base of the bridge, and 30 said wire is passed up over the upper bridge 2 and down to the lower bridge 2, where it is looped around the bottom screw 3 and the end 5 thereof, then returned back up to the upper screw 3 and looped upon said screw. 35 Each of the bridges 2 are provided with a pair of spaced grooves 6' therein and the opposite lengths 6 and 7 of wire 4 lie in said grooves and are thus maintained in spaced parallel relation. The grooves in each bridge, space 40 the wires 6 and 7 apart a selected distance and also space said wires away from the face of the jamb a selected distance.

The wire guiding structure thus far described is for use in connection with a Venetian blind which is positionable within a 45 window or door opening.

Where it is desirable to have a Venetian blind positionable outside of and over and across a window or door opening, it is necessary to use a modified form of structure for 50 supporting the guiding wires in vertical position. To accomplish this, I use the structure shown in Figs. 7, 8, 9 and 10. The modified form of the invention consists of a bracket 7', secured to the face of the casing or other trim upon a window or door opening, said bracket having an eyelet 8 arranged 55 in the extended end thereof, in substantially a perpendicular position. The eyelet is provided with two depressions 9 therein, for holding the guiding wires, to be hereinafter described, in a relatively vertical position. A bracket 10 is provided at the lower end of the casing, having a plate 11 with a slot 12 therethrough, through which the guide wires 60

are adapted to pass. A shoulder or hook 13 is provided on the bracket 10 below the slot 12. A guide wire has one end 14, thereof, attached to one side of the eyelet 8, said wire extending down through the slot 12 in the bracket 10 around the bottom of the shoulder 13, and is returned upwardly parallel with the other end of the same wire into connection with the eyelet 8. The two lengths of wire are maintained in spaced parallel relation, the same as the wires in the preferred form of the invention. By making both of the wire guides out of the same strand of wire, it is possible to draw both sides of the same into a relatively taut position merely by drawing up one end of the wire tightly upon the eyelet or screw to which it is fastened. The eyelet 8 is held in the upper bracket 7' by an adjusting nut 15 which can be moved on the threaded shaft of the eyelet to regulate the tension on the guide wires. 85

The strips of the Venetian blind are indicated by the numeral 16. Each strip 16 at each of the opposite ends thereof, is provided with a slide plate thereon consisting of a base portion 17, extended neck 18, and head portion 19. The base of the slider may be located in any desired position relative to the end of the strip, for the purpose of spacing the head 19 thereon in proper relation to the guide wires, so that the said neck piece is free to slide up and down between the guide wires, irrespective of the position of angularity of the strips of the Venetian blind. The head 19 on the slider has a length greater than the width between the guide wires, so as to normally resist displacement from between the guide wires. The strips of the Venetian blind normally assume a substantially horizontal position or an angular position closely approaching the horizontal, and the over-all length of the head on the slider is such as to retain the said strips in sliding position at all times. However, in order to remove any selected slider from sliding confinement between the guide wires, it is only necessary to place the strip in a relatively vertical position whereby the head on the slider will readily pass out from between the guide wires. 100

The method of operation of the slider in either the preferred or modified forms of the invention is identically the same. I have found that a guiding apparatus constructed in accordance with my invention operates more efficiently within wire guides of the form shown than when arranged between any other type of guiding apparatus, and furthermore, the wire guides can be installed more cheaply and quickly than any other type of guiding mechanism. 115

Having thus described this invention, what I claim and desire to secure by Letters Patent is:

1. A guide for a window shade comprising 130

a pair of wires arranged in spaced parallel relation at a side of the shade; and a plurality of slides arranged in spaced relation along said side of the shade, slidably confined by the wire guides.

5. 2. A guide for a window shade comprising a pair of wires arranged in spaced parallel relation at a side of the shade; and a plurality of slides, arranged in spaced relation along 10 said side of the shade, each slide consisting of a flat base secured to the shade, a rounded neck on the base extended between the wire guides and an elongated head on the neck positionable at the rear of the wire guides, 15 to confine the wire guides between the head and base in all movements of the shade.

3. A guide for a Venetian blind consisting of a pair of wires arranged in spaced parallel relation at a side of the blind; and a slide 20 attached to an end of each of the strips forming the blind, slidably confined by the wire guides.

4. A guide for a Venetian blind consisting of a pair of wires arranged in spaced parallel 25 relation at a side of the blind; a slide attached to an end of each of the strips forming the blind, each slide consisting of a flat base secured to the strips on the blind, a rounded neck on the base extended between the wire 30 guides, and an elongated head on the neck positionable at the rear of the wire guides, said neck in all movements of the blind being slidably confined by the wire guides.

5. A guide for a Venetian blind consisting 35 of a pair of wires arranged in spaced parallel relation at a side of the blind; a bridge member to hold the wires a selected distance apart; and a slide attached to an end of each of the strips forming the blind, slidably confined by the wire guides.

6. A guide for a Venetian blind consisting of a pair of wires arranged in spaced parallel relation at a side of the blind; a bridge member to hold the wires a selected distance 45 apart; a slide attached to an end of each of the strips forming the blind, each slide consisting of a flat base secured to the strips on the blind, a rounded neck on the base extended between the wire guides, and an elongated head on the neck positionable at the rear of the wire guides, said neck in all movements of the blind being slidably confined by the wire guides.

7. A guide for a Venetian blind consisting 55 of a pair of wires arranged in spaced parallel relation at a side of the blind; means to regulate the tension of the guide wires; and a slide attached to an end of each of the strips forming the blind, slidably confined by the 60 wire guides.

8. A guide for a Venetian blind consisting 65 of a pair of wires arranged in spaced parallel relation at a side of the blind; means to regulate the tension of the guide wires; a slide attached to an end of each of the strips

forming the blind, each slide consisting of a flat base secured to the strips on the blind, a rounded neck on the base extended between the wire guides, and an elongated head on the neck positionable at the rear of the wire guides, said neck in all movements of the blind being slidably confined by the wire guides.

In testimony whereof, I have hereunto set my hand at San Francisco, California, this 7th day of February, 1929.

THOMAS E. McNULTY.
